LARS A. JEFFERSON, OF BRIDGEPORT, CONNECTICUT.

Letters Patent No. 87,262, dated February 23, 1869.

IMPROVEMENT IN BUTTONS.

The Schedule referred to in these Letters Patent and making part of the same.

To all whom it may concern:

Be it known that I, LARS A. JEFFERSON, of Bridgeport, in the county of Fairfield, and State of Connecticut, have invented a new Improvement in Shirt-Stud; and I do hereby declare the following, when taken in connection with the accompanying drawings, and the letters of reference marked thereon, to be a full, clear, and exact description of the same, and which said drawings constitute part of this specification, and represent, in—

Figure 1, a side view;

Figure 2, an under-side view;

Figure 3, an upper-side view, the ornamentation removed to show the arrangement of the spring; and, in Figure 4, a sectional view enlarged.

This invention relates to an improvement in shirt-studs, the object being to facilitate the adjustment of the stud; and

The invention consists in the combination of a divided head, the two parts hinged together, and attached to the shank of the principal head, through which said shank a headed spindle passes, provided with a spring, which forces the said spindle against the joint of the divided head, so that the force of the said spring will retain the divided head either in a closed or flat open position.

In order to the clear understanding of my invention, I will fully describe the same as illustrated in the accompanying drawings.

A is the head, or base, which is covered with any ornamentation desired.

B, the shank, fixed to or made a part of the said head A.

To the said shank, are hinged the two parts, *a a*, of a divided head, so that the said two parts may be folded or opened, as denoted in fig. 4.

Through the shank passes a spindle, *d*, formed with a head, *c*, resting against the hinge of the two parts *a*, and upon the opposite end of the said spindle is arranged a spring, *f*, (see fig. 3,) so as to bear upon the said spindle with sufficient force to prevent the accidental turning of the parts *a a*.

To insert the stud, fold the two parts *a* together, as seen in fig. 4, and when inserted, open the two parts, as also seen in fig. 4, the spindle *d* holding the parts, when turned into either position, by the pressure of the spring thereon.

Having fully described my invention,

What I claim as new and useful, and desire to secure by Letters Patent, is—

The two parts *a*, of the one head, hinged together upon the shank *B*, of the other head, and combined with the spindle *d*, through the shank, so as to operate substantially in the manner set forth.

LARS A. JEFFERSON.
